UNITED STATES PATENT OFFICE.

STEVEN MAGAMI, OF KAMLOOPS, BRITISH COLUMBIA, CANADA.

SLATE-PENCIL HOLDER.

1,244,877.

Specification of Letters Patent. Patented Oct. 30, 1917.

Application filed March 23, 1917. Serial No. 157,004.

To all whom it may concern:

Be it known that I, STEVEN MAGAMI, a British subject, residing at Kamloops, in the Province of British Columbia, Canada, have 5 invented certain new and useful Improvements in Slate-Pencil Holders, of which the following is a specification.

This invention relates to a slate pencil holder which is a relatively permanent attachment to and is embedded in the wooden frame of an ordinary school slate.

The construction and manner of mounting the attachment of the device are fully set forth in the following specification, reference being made to the drawings which accompany it, in which:

Figure 1 is a plan of the slate showing the holder in position.

Fig. 2 shows in perspective the frame and 20 cover of the pencil receptacle, and

Fig. 3 is a cross section of the device as secured in the wooden frame of the slate.

Fig. 4 is a detail description showing the 25 resilient locking means for holding the cover in the closed position.

In these drawings 2 represents the wooden frame of the slate in one of the longitudinal members of which a groove 3 is cut, somewhat as shown in Fig. 3 of the drawing. 30 Over this groove 3 a facing frame 4 stamped from thin sheet metal is recessed into the face of the wooden frame 2 to extend along the back and across each end, the inner edge of the back portion substantially alining 35 with the corresponding edge of the groove 3. From the inner edge of each end of this facing frame 4 portions 5 are bent downward to the approximate depth of the groove 3 and the lower back ends of these have 40 rounded inward projections 6 designed to exercise a resilient grip on the ends of the cover to be described. This cover 7 is also formed of thin sheet metal. The front edge is approximately in line with the inner edge 45 of the frame 2 of the slate and along the back is bent at right angles, as at 8. At each end portions 9 are bent down to the approximate depth of the groove 3 in the slate frame and are formed with a slight hollow 50 at 10, conforming with the rounded projection 6 of the ends 5 of the facing frame.

In the extreme corner between the front face and back edge of this cover 7 a small aperture 12 is provided at each end for a hinge pin 11, which pin is embedded in the 55 wood of the frame and projects into the

space of the groove. The cover 7 is preferably stamped with apertures 13 to reveal the presence of a pencil, if one is in the receptacle.

The cover being placed in position in the groove 3 the hinge pins 11 are inserted through the pin holes 12 and the facing frame 4 is placed in position and is secured by screws or rivets to the frame of the slate. 65 When so secured the rounded end projections 6 of the frame 4 and corresponding hollow 10 of the cover ends 9 will retain the cover in the closed position, the resilience of the end pieces 5 of the facing frame pressing the 70 same into engagement, but this resilient engagement permits the cover to be readily opened turning on the pivot pins 11 and in so opening the receptacle the back portion 8 of the cover will deliver a pencil lying in 75 the groove 3 out upon the slate.

The device supplies a felt want in providing a simple means by which a slate pencil may be always kept in relation to the slate, and in a manner that does not form 80 a projection from that slate to be in the way of packing or to be liable to injury when the slate falls. The apertured cover enables the child or teacher to see at a glance that the slate is provided with a pencil and 85 the manner by which the opening of the cover delivers the pencil forms an advantageous feature.

It will also be noticed with my construction by hinging the cover on the back of the 90 pocket or recess so that it opens inwardly toward the slate the pencil when raised out of the pocket by the opening of the cover, may be delivered directly on the slate and all danger of falling on the floor and breaking 95 is thus avoided, a very advantageous feature, when it is considered that with slate pencils as usually made of a thin strip of slate, they are very brittle and easily broken when the same are dropped.

Having now particularly described my invention, I hereby declare that what I claim as new and desire to be protected in by Letters Patent, is:

1. A pencil holder for a school slate, comprising the combination with a slate frame having a grooved receptacle along one of its sides, a facing frame of thin sheet metal extending along the back and across each end of the grooved receptacle, an apertured 105 cover fitting the space between the back and sides of the frame and hinged along the

- back, said cover having a portion bent from its back edge and projecting into the receptacle and resilient means for retaining the cover in the closed position.
5. A pencil holder for a school slate, comprising the combination with the frame of a slate having a grooved receptacle along one of its sides, a facing frame of thin sheet metal extending along the back and across each end of the grooved receptacle, said frame having a portion bent from the inner side of each end to project into the receptacle, an apertured cover fitting the space between the back and sides of the frame and 10 having a portion bent from its back edge to project into the receptacle and a portion bent from each end to bear against the inwardly bent portions of the facing plate, hinge pins secured under the frame on 15 which pins the cover is mounted and engaging projections on the inwardly bent ends of the facing plate and inwardly bent ends of the cover to retain the cover in the closed position.
3. A pencil holder for a school slate comprising in combination with the frame of the slate having a grooved receptacle along one of its sides, a facing frame of thin sheet metal extending along the back on the outside of the frame and across each end of the grooved receptacle, said facing frame having a resilient portion bent from the inner side of each end to project into the receptacle and provided with a teat, an apertured cover fitting the space between the back and sides of the frame and having a portion bent from its back edge to project into the receptacle, and end portions bent from the respective ends to bear against the inwardly bent portions of the facing plate 40 and having depressions to receive the teat when the cover is closed, hinge pins for pivoting the cover on a longitudinal axis passing substantially through the corner edge of the cover substantially as shown and 45 for the purposes described.

In testimony whereof I affix my signature.
STEVEN MAGAMI.
